Gifford & Brown

UNITED STATES PATENT OFFICE.

WILLIAM F. FOLMER, OF NEW YORK, N. Y., ASSIGNOR OF ONE-HALF TO
WALTER E. SCHWING, OF SAME PLACE.

GAS-BURNER FOR BILLIARD-TABLES.

SPECIFICATION forming part of Letters Patent No. 397,904, dated February 19, 1889.

Application filed July 27, 1888. Serial No. 281,209. (No model.)

To all whom it may concern:

Be it known that I, WILLIAM F. FOLMER, of New York, in the county of New York and State of New York, have invented a certain 5 new and useful Improvement in Gas-Burners for Billiard-Tables, of which the following is a specification.

I will describe a gas-burner embodying my improvement in detail, and then point out the 10 novel features in claims.

In the accompanying drawings, Figure 1 is a side elevation of a gas-burner embodying my improvement. Fig. 2 is a rear elevation of the same. Fig. 3 is a vertical section of a 15 portion of the burner, taken on the plane of the line x x , Fig. 1. Fig. 4 is a transverse section of the same, taken on the plane of the line y y , Fig. 3.

A designates a gas-supply pipe, which may 20 extend from any suitable fixture.

B designates the shell of a gas-cock, secured to the supply-pipe A by means of a nipple or coupling-piece, a, on the shell of the cock.

C designates the plug of the cock. The 25 plug of the cock for that portion thereof which extends into the shell is made tapering and fits a correspondingly-tapered cavity in the shell. The plug is provided with a longitudinally-extending gas-passage, a', and another 30 gas-passage, a'', opening at one end into the gas-passage a', but extending at approximate right angles to the latter. The passage a'' also opens into a central cavity, a³, formed in a nipple or nozzle, C', made as here shown, integral with the main body of the plug of the 35 cock and extending at approximate right angles thereto beyond the shell B.

Communication between the supply-pipe A and the gas-passage a' of the plug is afforded 40 by means of a short gas-passage, a⁴, extending at approximate right angles to the passage a' and occupying such position in the plug that when the latter is rotated sufficiently far the passage from the supply-pipe and the passage 45 a' will intercommunicate. It is not intended in practice, however, that the communication between the supply-pipe A and the passage a⁴ shall ever be wholly closed. To accomplish this I provide the plug of the cock with a circumferential groove, a⁵. (Shown in Figs. 3

and 4.) This groove affords communication between the gas-supply pipe and the passage a⁴. I prefer to make the groove tapering. In other words, it will be deepest where it joins the passage a⁴, and will gradually vanish upon 55 the surface of the plug. The object of this will be more fully explained hereinafter.

One end of the shell B of the cock is shown as recessed. Within this recess is arranged a coil-spring, b. This coil-spring surrounds 60 an outwardly-extending portion, b', of the plug of the cock. It abuts at one end against the shell of the cock and at the other against a washer, b². Outward movement of the washer b² is prevented by means of a cross-bar, D, 65 rigidly secured to the portion b' of the plug of the cock. The spring b operates to hold the plug of the cock firmly in its seat. The outer end of the portion b' of the plug is grooved to receive the cross-bar D, and the 70 latter is secured at about midway in its length within said groove, as here shown, by means of a screw, c. The cross-bar D is employed to rotate the plug of the cock. I have shown chains d secured to the cross-bar near the ends 75 of the latter. By pulling upon one or the other of these chains, as required, the plug of the cock may be rotated in any desired direction. The cavity a³ in the nozzle or nipple C' of the 80 plug is internally screw-threaded to receive a pipe, d². In the other end of the pipe d² is secured a burner-tip, d³. The pipe d² and the tip d³ constitute the burner proper.

E designates a globe, of glass or similar material. This globe rests at its lower edge 85 in a metallic globe-holder, e, which latter is provided centrally with an opening through which extends the pipe d². The globe-holder is also perforated to form an air-distributer. Its outer edge is turned upwardly to form a 90 flange, e', extending about the lower edge of the globe. Lips or lugs e² on the flange e' may be bent over the lower edge of the globe to retain the latter in position. The globe-holder e has a pivotal connection with one 95 end of a link, F. The latter near its other end is in the example of my improvement shown provided with a longitudinal slot, f. Into this slot extends a pin, f', which latter extends from an arm, G, rigidly mounted on 100

the shell B of the cock. When the plug of the cock is rotated by means of the cross-bar D in such manner as to throw the pipe d^2 into the position shown in dotted outline in Fig. 5 1, not only is the gas turned on, but the globe E is moved backwardly along the pipe d^2 and away from over the tip d^3 , so that a full flame of gas may issue from the tip. The rotation of the plug of the cock in the other direction, 10 or in the direction to turn the gas off, throws the arm d^2 into the position shown in full lines in Figs. 1 and 2 and causes the globe E to be moved along the pipe d^2 and into a position to surround the tip of the burner. When being moved into the latter position, the gas is 15 cut off gradually, owing to the tapering groove a^5 in the plug, until when in the extreme positions illustrated in full lines in Figs. 1 and 2 a mere thread of flame may, if desired, be 20 left at the burner-tip, which, owing to the protection of the globe E, will not be extinguished by gusts of air.

By providing the link F with a longitudinal slot at its point of connection with the arm G 25 the plug of the cock may be rotated for a considerable distance without effecting any movement of the globe E, because the link F will slide along on the pin f' . By this means danger of breaking the globe is avoided, as the 30 flame will not be of sufficient dimensions at any time while the tip is within the globe to come in contact with it and cause fracture.

It will be seen that the shell of the cock is provided with a projection, g , and that the 35 cross-bar D is provided with adjustable stops g' , adapted to contact with the projection g as the cross-bar is moved in either direction. These adjustable stops in this example of my 40 improvement consist of screws working in tapped holes in the cross-bar D. By manipulating these stops a less or greater range of movement may be given to the cross-bar, and consequently to the plug of the cock, whereby a greater or less supply of gas may be allowed to pass to the burner-tip, as desired.

I have shown a smoke bell or reflector, H, supported from an arm, h, secured to the pipe A. This smoke-bell will preferably be of such

size as to always be in proper position above the burner.

By my improvement I provide a means for always maintaining a light at the burner-tip and for readily bringing the burner into a proper position above a billiard-table, while by this movement the gas is turned on in the 55 desired force. I also provide means for readily varying the flow of gas.

What I claim as my invention, and desire to secure by Letters Patent, is—

1. The combination, with a gas-supply pipe, 60 of a gas-cock having a rotary plug, and a gas-burner secured to said plug and moving therewith to occupy substantially vertical and horizontal positions, and a globe connected to said gas-cock and sliding on the burner as it 65 is moved from one position to the other, substantially as specified.

2. The combination, with a gas-supply pipe, 70 of a gas-cock having a rotary plug, a gas-burner secured to said plug and having a movement therewith to occupy approximately vertical and horizontal positions, a globe for the burner, a rigid support, and a swinging connection between the globe and said support, whereby when the burner occupies a vertical 75 position the globe will surround the burner-tip, and when the burner occupies a horizontal position the globe will be moved from over the burner-tip, substantially as specified.

3. The combination, with a gas-supply pipe, 80 of a gas-cock having a rotary plug, a gas-burner secured to said plug and moving therewith to occupy approximately vertical and horizontal positions, a globe for the burner surrounding the burner-tip when in one position and removed from said tip when in its other position, a rigid support, and a link having a pivotal connection with said globe near one end and having a slotted connection with said support near the other end, substantially as specified.

WILLIAM F. FOLMER.
